UNITED STATES PATENT OFFICE.

HENRY SCHUMACHER, OF BUFFALO, NEW YORK.

ASPHALT-CUTTER.

1,250,521.

Specification of Letters Patent. Patented Dec. 18, 1917.

Application filed March 21, 1917. Serial No. 156,406.

To all whom it may concern:

Be it known that I, HENRY SCHUMACHER, a citizen of the United States, residing at Buffalo, in the county of Erie and State 5 of New York, have invented new and useful Improvements in Asphalt-Cutters, of which the following is a specification.

This invention relates to an asphalt cutter which is more particularly designed for cutting 10 grooves, channels, or furrows in asphalt pavements for the purpose of facilitating repairing of the same and also to expedite the digging of trenches below the pavement in which to lay sewer, gas, water or other 15 pipes and conduits for telegraph, telephone and electric light and power wires, and for other purposes.

It is the object of this invention to provide a machine whereby the work of cutting 20 the asphalt pavement in this manner can be effected quickly, easily and economically and with a minimum expenditure of manual labor.

In the accompanying drawings:

25 Figure 1 is a side elevation of an asphalt cutting machine embodying my invention. Fig. 2 is a top plan view of the same. Fig. 3 is a vertical longitudinal section thereof, taken on line 3—3, Fig. 2. Fig. 4 is a front elevation of the machine, partly in section. Fig. 5 is a vertical transverse section of the machine taken on line 5—5, Fig. 2, looking forwardly. Fig. 6 is a fragmentary vertical transverse section, on an enlarged scale, 30 taken on line 6—6, Fig. 2. Fig. 7 is a vertical section taken on line 7—7, Fig. 6. Fig. 8 is a fragmentary vertical section taken on line 8—8, Fig. 5. Fig. 9 is a detached elevation of one of the cutting tools. Fig. 10 is a fragmentary horizontal section of a pair 35 of tools showing the manner in which they operate for producing a groove or furrow in the surface of the asphalt pavement.

Similar characters of reference indicate 40 corresponding parts throughout the several views.

The main frame of this machine may be 45 of any suitable construction to support the different working parts of the machine, but 50 in the preferred form shown in the drawings, the same comprises two upright longitudinal side pieces, beams, sills or girders 1, 2, a central longitudinal girder or beam 3 arranged midway between the side girders, a cross piece 55 4 connecting the front upper parts of these girders, a transverse tie rod 5 connecting the

front parts of these girders and surrounded between the respective girders by spacing sleeves 6 and an intermediate transverse tie rod 7 connecting the intermediate parts of 60 the girders and surrounded between the respective girders by spacing sleeves 8, as shown in Figs. 1, 2, 3 and 5. This frame in effect forms the body of a carriage which is provided with wheels so that the same 65 may be readily transported as the cutting of the asphalt progresses and also for shifting the machine quickly from one job to another and to and from the place where the same is being stored. The preferred 70 means for this purpose which are shown in the drawings comprise two pairs of traction or driving wheels 9, 10 which are arranged axially in line transversely of the machine at the rear end thereof, a pair of these 75 wheels being preferably arranged between the intermediate girder and each of the side girders, as shown in Figs. 2, 4 and 5. The front of the machine is provided with a pair of steering wheels 11 which are preferably 80 arranged in recesses 12 formed in the lower front corner of the side girders of the main frame, as shown in Figs. 1—4. These steering wheels may be mounted in any suitable manner but preferably in the 85 manner now in common use in automobiles. As shown in the drawings, the mounting of these steering wheels comprises a horizontal steering axle 13 arranged transversely below the front part of the intermediate girder 90 and connected with opposite sides of the latter by means of brackets 14 and also connected near its opposite ends with the front parts of the side girders by means of side brackets 15, two horizontally-swinging 95 steering knuckles 16 which are pivoted to turn vertically in bearings arranged at opposite ends of the steering axle and pivotally supporting the steering wheels, respectively, a transverse equalizing rod 17 connecting two rearwardly-projecting arms 18 on the steering knuckles, and an upright steering post or shaft 19 journaled in suitable bearings on the central part of the intermediate girder and provided at its upper 100 end with a steering wheel or handle 20 while its lower end is provided with a rock arm 21 which is connected by means of a shifting rod 22 with a shifting arm 23 arranged on one of the steering knuckles, as shown 110 in Figs. 2, 3 and 4.

Although various means may be provided

for propelling the carriage forwardly and backwardly, those which are shown in the drawings are preferred and constructed as follows:

- 5 24 represents a motor, preferably of the explosion type, mounted on the front part of the main frame or body of the carriage and having a horizontal transverse driving shaft 25 which is provided with a driving gear wheel 26. A speed changing shaft is journaled horizontally and transversely in suitable bearings on the main frame in rear of the driving shaft and has a driving section 27 and a driven section 28 which are connected by speed changing device 29 of any suitable character so that the driving section 27 may turn continuously in the same direction while the driven section 28 may be either coupled with or uncoupled from the driving section or turned in either direction relatively to the driving section. Inasmuch as any suitable speed changing mechanism may be employed, no details of the same are shown.
- 25 The driving section 27 of the speed changing shaft is driven by means of a gear wheel 30 secured thereto and meshing with the driving wheel 26 of the motor shaft.
- 31 represents a countershaft which is journaled in suitable bearings on the girders of the main frame in rear of the speed changing shaft 27, 28. On the central part of this countershaft is loosely mounted a gear wheel 32 which meshes with a gear wheel 33 secured to the driven section of the speed changing shaft. The gear wheel 32 may be connected with the countershaft so as to turn therewith or disconnected therefrom so as to turn independently of this shaft by means 40 of a clutch which preferably comprises a clutch sleeve 34 slideable lengthwise upon the countershaft but compelled to turn therewith by means of a spline and provided with clutch teeth which engage with corresponding clutch teeth on the hub of the gear wheel 32. When the teeth of the clutch sleeve 34 and the gear wheel 32 are coupled, then the power of the motor 24 is transmitted to the countershaft providing the speed changing mechanism has been operated to connect the driving and driven shaft sections 27, 28, while upon withdrawing this clutch sleeve so as to disengage its teeth from those on the hub of the gear wheel 32, then the countershaft will be unaffected by the motor. The carriage is propelled at a relative high rate of speed by means of two driving chain belts 35 each of which passes around a driving sprocket wheel 36 mounted loosely on one end of the countershaft and a driven sprocket wheel 37 secured to the outer end of the outer member 9 of one pair of traction wheels, as shown in Figs. 1, 2 and 5. Each driving sprocket wheel 36 may be connected 60 with or disconnected from the countershaft

by means of a clutch which, in the example shown in Figs. 2 and 6, comprises a clutch sleeve 38 connected by means of a spline with the countershaft and provided with clutch teeth which are adapted to be engaged with or disengaged from clutch teeth on the hub of the respective driving sprocket wheel 36.

The clutch sleeves 34, 38, 38, may be shifted into and out of their operative positions in various ways, for instance, by means of forks 39, 40, 40 engaging annular grooves in these clutch sleeves, upright shafts 41, 42, 42 journaled in suitable bearings on the main frame and carrying these forks, respectively, at their lower ends, and handles 43, 44, 44 secured to the upper ends of these shafts and arranged within convenient reach of the operator who has control of the machine. When the clutches 34, 38, 38 are in operation, the machine may be propelled at a comparatively rapid rate over the ground, it being operated in this manner when transported to and from the plant to the job, and from one job to another. When, however, the machine is engaged in cutting a groove or a furrow in an asphalt surface, the same is either pushed forwardly by hand, or the same may be pushed forwardly by power derived from the motor 24. For this purpose the following mechanism is provided, parts of which are also used for accomplishing other purposes:

45 represents an operating shaft journaled horizontally and transversely in appropriate bearings on the girders of the main frame. This shaft is turned by power in the direction of the arrow 45^a, Fig. 2, by means of gear pinions 46, 46 and engaging with gear wheels 47, 47 secured to the ends of the operating shaft, as shown in Fig. 2. Each of the driving pinions 46 is mounted on the countershaft so as to be compelled to turn forwardly with the same but incapable of turning backwardly therewith, this being accomplished for instance, as shown in Figs. 6 and 7, by means of a ratchet mechanism interposed between each driven gear wheel 46 and the countershaft, which ratchet device may consist of a pawl 48 pivoted on the respective driving gear wheel 46 and engaging with a shoulder 49 on the adjacent part of the countershaft, as shown in Fig. 7.

On opposite sides of the intermediate girder of the main frame, the operating shaft is provided with two eccentrics 50 each of which is surrounded by an eccentric strap 51. 52 represents a ratchet wheel secured to that end of each inner traction wheel 10 which faces the intermediate girder and 53 represents a ratchet lever which is journaled on the hub of each ratchet wheel and provided with a dog or pawl 54 which is pivoted thereto and engages with the teeth of the companion ratchet wheel, and a connecting 130

rod 55 projecting rearwardly from each of the eccentric straps and pivotally connected at its rear end to the upper end of one of the ratchet levers, as shown in Figs. 2, 3 and 5. When the pawls 54 are in engagement with the ratchet wheels and the counter-shaft is turning forwardly, or in the direction of the arrow 56, while the clutch sleeves 38, 38 are withdrawn, from the driving 10 sprocket wheels 36, then the rotary movement which is imparted to the operating shaft causes the eccentrics 50, 50 to oscillate the ratchet levers and turn the inner traction wheels 10, 10 forwardly or in the direction of the arrow 57 in Fig. 3. By this means a comparatively slow forward movement is imparted to the carriage to suit the progress of the cutting tools which are at this time operating upon the asphalt surface. While the machine is being thus propelled slowly, the quick propelling mechanism is rendered inoperative and when the quick propelling mechanism is in use, the pawls 54 of the ratchet levers are thrown 20 backwardly out of engagement from the ratchet wheels and against stop pins 58 in which position the pawls or dogs are inoperative and the ratchet levers are merely oscillated idly at such time as the machine 30 is being propelled forwardly at a rapid rate by the motor.

The traction wheels 9, 10 may be mounted on the frame in any suitable manner but in order to permit of taking up the slack in 35 the driving chains 35 due to wear, these wheels are preferably mounted as follows:

59 represents a stationary arbor which is mounted horizontally and transversely on the lower rear parts of the girders and upon 40 which the two pairs of inner and outer traction wheels turn. The central part of this arbor is reduced to form a neck 60 and two inwardly-facing shoulders 61, 61. 62, 62 represent two sections of a clamping sleeve 45 which is split lengthwise and diametrically so that the same may be applied to the central reduced part 60 of the arbor and which is provided with outwardly-facing shoulders 63 in opposite ends of its bore which engage 50 with the shoulders 61 of the arbor in the assembled position of the parts, and thereby prevent this split sleeve from moving lengthwise on the arbor. This split clamping sleeve has the central part of its periphery 55 made square and arranged in a horizontal longitudinal slot 64 formed in the lower part of the intermediate girder, while the opposite ends of its periphery are provided with external screw threads which receive 60 internally-threaded clamping rings or nuts 65 engaging with opposite sides of the central frame-girder 3. By this means, these clamping nuts not only hold the two sections of the clamping sleeve against opposite sides 65 of the arbor but also clamp this sleeve on

the central girder, so as to securely attach the central part of the arbor to the central part of the frame. At each of its outer ends, the arbor passes through a supporting sleeve which is adjustable lengthwise 70 on the adjacent part of the respective side girder. This sleeve, as shown in Figs. 1 and 5, preferably comprises a square hub 66 movable lengthwise in a longitudinal slot 67 formed in the adjacent part of the respective side girder and provided on its inner end with an integral flange 68 which engages with the inner side of the respective girder while the outer end of this hub is provided with a removable flange 69 which is detachably secured thereto by means of screws 70 and engages with the outer side of the respective side girder. This adjusting sleeve may be moved rearwardly and held in its adjusted position by means of the horizontal 80 adjusting screw 71 arranged in a flange 72 on the side girder adjacent to the front end of its slot 67 and bearing with its rear end against the hub 66 of the adjusting sleeve and a clamping nut 73 applied to said 90 adjusting screw and bearing against the respective flange 72 in which said screw is mounted.

By adjusting the central supporting sleeve 62 and the side supporting sleeve 66 horizontally with reference to the frame, the position of the arbor 59 may be shifted as required to suit the driving chains 35 and permit of taking up wear whenever this is necessary. Outside of each of the outer 100 guide sleeves 66 a retaining pin 74 passes transversely through the same so as to prevent the lower parts of the side frames adjacent to the traction wheels from spreading thereby utilizing the arbor not only as a 105 means for supporting the traction wheels on the main frame, but also stiffening this part of the frame and enabling it to resist side strains effectively without requiring the machine to be made unduly heavy. 110

The means for cutting or chopping the asphalt surface and forming the groove, channel or furrow therein in accordance with my invention, is constructed as follows: 115

75, 75 represent two vertically-swinging helves or cutter arms which are preferably constructed of wood so as to secure the necessary resilience, although the same may be made of other material. These helves are 120 pivotally mounted at their inner or front ends on the main frame and the tools or cutters which operate upon the asphalt surface are mounted on their outer or rear ends so that upon oscillating the same the 125 tools will be intermittently raised from the asphalt surface and then swung downwardly so that they dig or cut into the asphalt. Two of such helves are preferably arranged as a pair and are so mounted in the ma- 130

chine that they converge rearwardly from their front ends and their rear ends are arranged close together. The driving mechanism associated with these helvés is so constructed and operated that the same are raised and lowered alternately, whereby the two tools of the helvés are caused to operate successively on the asphalt and form opposite sides of a groove or channel therein.

10 During the operation of a pair of these cutters the same remove that part of the asphalt surface which is arranged between the two cutting lines in a manner substantially like that in which this is now done by manually operated tools. In order to produce this effect, the operative cutting bit 76 of the tool which at this time is on the underside of the helve has its lower sharpened or cutting edge 77 arranged obliquely or at an angle relative to the length of the helve, so that the cutting edges of the two bits which for the time being are in the operative or cutting position diverge forwardly to a greater extent than the forward divergence 25 of the helvés, as shown in Fig. 2. By this means each bit upon striking the asphalt produces not only a cutting action thereon but also a prying action toward the other bit, so that between the cutting and prying operation by both operative bits, the asphalt surface between the two cutting lines of these bits is quickly and effectively removed to form a groove or channel in the asphalt.

30 35 Each bit preferably has its cutting edge so arranged relatively to the respective helve so as to form two cutting corners 78, 78 at opposite ends of the cutting edge. In operation, the bit upon striking the asphalt surface digs with its rear corner into the asphalt, as shown in Figs. 1 and 3, so that this corner receives the greatest amount of wear. Means are therefore provided for permitting this bit to be reversed fore and aft on 40 the helve, so as to bring the previously un-worn cutting corner into the rearmost or operative position. In order to avoid interrupting the operation of the machine as little as possible, the tool of each helve is preferably made with two bits, one of which projects downwardly from the helve while in use while the other projects upwardly therefrom and is held in reserve, both bits being preferably formed integrally with and 45 on opposite sides of a central socket, hub or sleeve 79 which is mounted on the rear end of the respective helve in a manner resembling an ordinary hand-operated pick axe. When thus organized the edges of the bits 50 55 60 65 on opposite sides of the hub incline in opposite directions relative to the axis of its hub, so that when the tool is reversed end for end to bring either bit into the lower operative position or the same is reversed fore and aft, so that either corner of the

bit is brought into the working position, then the lower cutting edge of each bit will be arranged at the proper angle relative to the asphalt to produce the combined cutting and prying action above referred to. Each 70 of the helvés preferably enlarges from its central part toward its front and rear ends and the bore of the hub of the tool is of forwardly-tapering form so that when the latter is applied to the helve it will not permit rearward movement of the tool on the helve while cutting blows are delivered against the asphalt surface. The rear part of each helve and the bore of the socket in the tool is also preferably of oval form, so 75 that the tool will not turn on the helve while the same is in use. The front end of each helve is preferably of smaller cross sectional dimensions than the rear end thereof, so that the hub of each cutting tool may be 80 slipped forwardly off from the helve and then turned end for end or reversed fore and aft for bringing the desired corner of the tool to the working position. By this means a very simple and reliable connection 85 is provided between the helve and the tool which holds the latter effectively in place and also permits of readily adjusting the tool for successively using different parts thereof.

90 The preferred means for pivotally mounting the helvés at their front ends on the rear part of the main frame, as shown in the drawings, are constructed as follows:

fore and aft on the helve, or turn the same upside down, for bringing different corners thereof into working position, the front end of the helve is removed from the pivot socket 5 and then replaced after the tool has been shifted into the desired position.

Each of the helves is preferably so operated that it is slowly raised by power and then thrown down quickly so as to deliver a 10 hammer blow against the asphalt. The means whereby this is accomplished are shown in Figs. 1-5, and are constructed as follows:

86 represents a shifting arm projecting 15 upwardly from each of the pivot sleeves 80. In front of each of these shifting arms is arranged an upright shifting rod 87 which is provided at its upper end with a bifurcated head 88 which is pivotally secured to 20 the upper end of one of the shifting arms by means of a transverse pin 89. 90 represents two cam bars arranged lengthwise in the spaces between the central and side girders below the operating shaft and each pivotally 25 and adjustably connected at its rear end with the lower end of one of the upright shifting rods 80 which connection is preferably effected by means of an adjusting sleeve 91 provided with an internal screw 30 thread engaging with an external screw thread on the lower end of the respective shifting rod 87 and a transverse pivot pin 92 passing horizontally through the rear end of the cam bar, and a pair of lugs 93 on the 35 front side of the adjusting sleeve 91, as best shown in Figs. 2 and 3. At its front end each of the cam bars slides through the front and rear cross bars 94, 95 of a yoke which has its side bars 96, 96 pivotally mounted by 40 means of pins 97 journaled in bearings 98 on the adjacent parts of the girders, as best shown in Figs. 1 and 4. 99, 99 represent springs surrounding the cam bars within the yokes and each bearing at its front end 45 against the front cross bar 94 of the respective yoke and at its rear end against a collar or shoulder 100 formed on the cam bar within this yoke. At its rear end each of the cam bars is provided on its upper side with a 50 bearing surface 101 which is adapted to be engaged by a roller 102 which is carried by the wrist 103 of a double-armed crank 104 formed on the adjacent part of the operating shaft, so that this roller in effect performs 55 the function of a cam. During each rotation of the operating shaft, each of the cam-rollers engages with the cam face of the cam bar and pushes the same downwardly and also forwardly whereby this cam bar is 60 caused to slide lengthwise in the yoke and the latter to turn on the girder, thereby causing the shifting rod 87 to pull forwardly and downwardly on the companion shifting arm and lift the rear end of the respective 65 helve together with the tool mounted thereon,

The instant the cam roller clears the front end of the bearing face of the cam bar, the latter is released and immediately returned to its rearmost and uppermost position by the spring 99 and thereby aids gravity in 70 quickly returning the tool into its lowered position. This quick return or downward movement of each cutting tool is further hastened by means of a depressing spring which is strained during the upward motion 75 of the helve and which operates to throw the latter downwardly with a powerful stroke the instant that the cam roller clears the bearing face of the cam bar and thereby cause the cutting edge of the tool to deliver 80 an effective blow upon the surface of the asphalt. Each of these depressing springs preferably comprises two coils 105, 105 arranged upon the pivot sleeve on opposite sides of its socket, pressure arms 106 connected with each other in the form of a loop and with the inner ends of these two coils and exerting pressure upon the upper side of the respective helve in rear of its pivot and two retaining arms 107 arranged at the 85 outer ends of these spring coils and engaging with the adjacent part of the main frame, as shown in Figs. 2 and 5. A wearing piece or cushion 108 of leather or similar material is preferably interposed between the upper 90 side of each helve and the loop arms of the depressing spring, as shown in Figs. 1, 2 and 3, for the purpose of deadening any noise by engagement of the depressing spring with the helve, and also to relieve the latter from 95 undue wear.

As the bits of the cutting tool become shorter by wear and repeated grinding or re-sharpening, it becomes necessary to lower the rear end of each helve in order to compensate for such wear. This is preferably accomplished by lengthening the connection between each cam bar and its shifting rod 87, by removing the upper head 88 of the shifting rod from the companion shifting 110 arm 86 and then unscrewing the lower end of this shifting rod from the adjusting sleeve 91, the requisite extent so that upon reconnecting the head with the shifting arm, the rear end of the helve will be lowered 115 sufficiently to permit the shortened bit to properly reach the asphalt surface.

The two cam rollers or cranks which operate the pair of helves are preferably arranged on diametrically opposite sides of 120 the operating shaft so that the cutting tools are raised and lowered alternately and at intervals of a half rotation of the operating shaft, thereby not only causing the tools to cut the asphalt in imitation of the manner in which this is now done by hand but also distributing the work of the motor more uniformly and avoiding undue wear upon the parts.

While the machine is being transported 130

without cutting asphalt, the two helves are preferably raised into an inoperative position in which the cam bars are lowered so that they are beyond the range of the cam 5 rollers and are uninfluenced thereby. This raising of the helves may be effected by manual means of any suitable construction, those shown in the drawings as an example consisting of two lifting levers 109 pivoted 10 on opposite sides of the upper rear part of the central girder and having their upper arms connected with each other while their rear arms are provided with laterally projecting fingers 110 extending underneath 15 the helves respectively, as shown in Figs. 1, 2, 3 and 5. During the operation of the machine, these lifting levers are so turned that their fingers are arranged below the lowermost position of the helves and do not 20 interfere with the free movement of the latter, but when the helves are to be shifted into their inoperative positions, the lifting levers are turned so that their fingers raise these helves into their highest position 25 where they remain unaffected by the mechanism which ordinarily actuates them. The lifting levers are retained in either one of these two positions by means of a hook 111 connected with the upper arms of the lifting 30 lever and adapted to engage either with the rear seat 113 on the main frame when the lifting levers are in an inoperative position, or with a front seat 112 on the main frame when the lifting levers raise the helves into 35 their inoperative position.

In the machine shown in the drawings, only two helves are shown which are provided with tools adapted to form a single groove or furrow in the asphalt. If desired, 40 however, a plurality of such pairs of helves and tools may be mounted side by side on the same frame, so that two or more grooves or channels may be cut simultaneously while the machine is moving over the asphalt. 45 For instance, if this machine is organized for cutting asphalt preparatory to removing the same in order to dig a narrow trench in which telephone, telegraph or electric light conduits are to be placed, two pairs of 50 cutter arms and tools are arranged side by side, the space between the two pairs of tools being equal to the width of the trench which is to be formed in the street to receive the conduits. 55 Owing to the ease with which the power may be applied either to the cutting tools or to the propelling mechanism for moving the machine either slowly or rapidly, it is possible to effect the cutting of asphalt 60 much more rapidly and at considerable less cost than has been possible by the means heretofore employed for this purpose. Moreover owing to the fact that the transverse tie rods or members which support various 65 working parts of the machine also serve to

connect the longitudinal girders, these transverse members in effect become a part of the main frame, thereby rendering the machine very strong and rigid and capable of withstanding heavy strains while in use 70 without necessitating making the same unduly heavy for this purpose.

I claim as my invention:

1. An asphalt cutter comprising a helve which enlarges from its central part toward 75 opposite ends, a tool having a tapering socket which receives the outer end of said helve, and a rocking socket of tapering form which receives the inner end of said helve.

2. An asphalt cutter comprising a helve which enlarges from its central part toward 80 opposite ends, a tool having a tapering socket which receives the outer end of said helve, and a rocking socket of tapering form which receives the inner end of said helve, 85 the inner end of said helve being smaller in cross section than the outer end thereof.

3. An asphalt cutter comprising a main frame, an arbor mounted on said frame, a pivot sleeve journaled on said arbor, a 90 socket having a relatively fixed section connected with said sleeve and a removable section detachably connected with said fixed section, a helve having its inner end secured in said section, and a tool mounted on the 95 outer end of said helve.

4. An asphalt cutter comprising a main frame, a helve pivotally mounted on said frame to swing vertically, a tool mounted on said helve, a spring for depressing said 100 helve, and means for lifting said helve comprising a cam bar movable vertically and lengthwise, a shifting arm connected with the helve, a shifting rod connecting said arm and bar, a spring operating to move said 105 bar upwardly and lengthwise and a rotatable cam engaging said bar and operating to move the same downwardly and lengthwise.

5. An asphalt cutter comprising a main frame, a helve pivotally mounted on said 110 frame to swing vertically, a tool mounted on said helve, a spring for depressing said helve, and means for lifting said helve comprising a cam bar movable vertically and lengthwise, a shifting arm connected with the helve, a shifting rod connecting said arm and bar, a spring operating to move 115 said bar upwardly and lengthwise, a rotatable cam engaging said bar and operating to move the same downwardly and lengthwise, and a yoke which is pivotally mounted on said frame and in which said cam bar is guided.

6. An asphalt cutter comprising a main frame, a helve pivotally mounted on said 125 frame to swing vertically, a tool mounted on said helve, a spring for depressing said helve, and means for lifting said helve comprising a cam bar movable vertically and lengthwise, an upwardly projecting shift- 130

ing arm connected with the helve, a coupling sleeve pivoted on the cam bar and having an internal screw thread, an upright connecting rod having its lower threaded end engaging with said coupling sleeve and its upper end pivotally connected with said shifting arm, and a rotatable cam engaging with said cam bar.

5 7. An asphalt cutter comprising a main frame, a helve pivotally mounted on said frame to swing vertically, a tool mounted on said helve, a spring for depressing said helve, and means for lifting said helve comprising a cam bar movable vertically and

lengthwise, an upwardly projecting shifting 15 arm connected with the helve, a coupling sleeve pivoted on the cam bar and having an internal screw thread, an upright connecting rod having its lower threaded end engaging with said coupling sleeve and its 20 upper end pivotally connected with said shifting arm, a rotatable cam engaging with said cam bar, a yoke which is pivoted to turn vertically on said frame and which is guided in said yoke, and a spring interposed 25 between said yoke and a shoulder on said bar.

HENRY SCHUMACHER.
